AIR CONDITIONING DEVICE

John M. Frank, Winnetka, and Walter H. Rietz,
Ravinia, Ill., assignors to Ig Electric Ventilat-
ing Company, Chicago, Ill., a corporation of
Louisiana

Application September 30, 1933, Serial No. 691,614

4 Claims. (Cl. 62—129)

This invention pertains to the general art of air conditioning devices, and has reference more particularly to devices for cooling and de-humidifying the air in the rooms of dwellings, office buildings, etc., in hot weather to increase the comfort and improve the efficiency of the occupants of such rooms. Of late years the use of built-in air conditioning systems in dwellings, office buildings, factories, and the like has become prevalent, and so great has become the demonstrated value of such systems that the demand therefor is growing rapidly.

Built-in air conditioning equipments are expensive, and, of course, when installed, are permanent as to location, and cannot be shifted from one room to another. Hence, in the case of office buildings for instance, to be practical, the equipment must be so extensive as to be able to serve all the rooms, and where a considerable number of rooms may be vacant, the equipment pertaining to such rooms represents an idle investment. Furthermore, with the frequent changing of tenants in an office building, the partition walls of the offices are constantly being changed, and, to the extent that the air conditioning equipment may be located in such partition walls, the rearrangement of the latter to suit the wishes or needs of tenants is rendered difficult and expensive. Furthermore, in the case of large rooms the cost of cooling the entire body of air in the room may be considerable, whereas the same individual comfort effect may be obtained at a considerably less cost by apparatus designed to direct a current of cool air toward or on one or more individuals in the room. And, in the latter case, where office desks may be shifted about from one place to another, a portable air cooling device, the position and directive discharge of which may be changed, is a manifest advantage.

The above and other considerations have led to the development of the present invention, the chief purpose or design of which has been the production of a simple, compact and improved portable air conditioning device of the compressor-condenser-expansion circuit type, that is entirely self-contained and preferably entirely automatic and may readily be moved from room to room or from one position to another in the same room, so as to discharge a stream of air directly toward an occupant of the room. Another object has been the production of such a device in the form or disguise of a neat and attractive article of furniture of the cabinet type, so as to avoid a clash with the other artistic equipment of the room or offense to the aesthetic

tastes of the occupant or visitors. Another object has been to provide means for more effectively ridding the chamber of the cabinet containing the motor and the compressor of the heat given off by said motor and compressor. And a further object has been to provide an improved means for cooling, cleaning and de-humidifying the air handled by the device and for conveniently disposing of the moisture of condensation, for which latter purposes the device may be portable or fixed.

Still other objects and attendant advantages of the invention will be apparent to persons familiar with this class of devices from the following detailed description, taken in connection with the accompanying drawings in which we have illustrated one practical and approved embodiment of the invention, and wherein:

Fig. 1 is a front elevation with the front panel removed to disclose internal parts.

Fig. 2 is a side elevation, viewed from the right of Fig. 1, with the side wall removed.

Fig. 3 is a top plan, with the top wall or cover removed.

Fig. 4 is a horizontal section taken on the line 4—4 of Fig. 1, looking downwardly.

Fig. 5 is a detail view of a flexible coupling intermediate the two compressor shafts.

Fig. 6 is a diagram showing certain leads and controls.

The entire equipment is contained within an upright cabinet comprising a removable rear wall or panel 10, side walls 11, an upper front wall 12, a bottom wall 13, a removable front panel 14 and a removable lid or cover 13'. A horizontal partition 15 divides the interior of the cabinet into a relatively small upper compartment 16 containing a fan and cooling coils, and a relatively large lower compartment 17 containing most of the operating equipment.

In the lower portion of the lower compartment 17 is mounted a skeleton platform 18, best shown in Fig. 4, supported on the bottom wall 13 by rubber mountings 19 on its sides and ends. Supported on the four corners of the platform 18 are angle bar uprights 20 which in turn support on their upper ends a top platform 21. Mounted on the platform 18 is an electric motor 22, and mounted on the upper platform 21 are twin gas compressors 23. The armature shaft of the motor 22 carries a pulley 24 connected by twin belts 25 to fly-wheel pulleys 26 respectively secured on independent crank shafts 27 of the two compressors 23. Owing to practical difficulties of driving both compressors from a single shaft, two

shafts 27 are employed, and, as shown in the detail view Fig. 5, the inner peripheries of the pulleys 26 are fastened together in proper phase relation of the compressors by means of flexible links or straps 28 located diametrically opposite each other. With this construction, in the event of uneven traction of the two belts 25, due to slip of one belt on the pulley 24 or 26, or for other causes, the operation of the two compressors is maintained substantially constant and uniform and in correct phase relation, and the described construction also eliminates the necessity of exact axial alignment of the bearings of the compressor shafts.

15 Also mounted on the platform 18 at one end thereof is a condenser housing 30 containing a condenser coil 31, a heat exchange coil 32, and a refrigerant tank 33.

Referring to Fig. 2, the front wall 12 of the upper compartment 16 is formed with a central opening 34, in front of which is rotatably mounted a deflector preferably equipped with oblique blades or louvers 35 and an operating knob 36. Directly in rear of the opening 34 is an air cooling and moisture reducing coil 37, leaning backwards, as shown in Fig. 2, to prevent condensate on the coil from being blown out onto the deflector blades 35, and directly in rear of the coil 37 is a propeller fan 38 driven by an electric motor 39. Directly in rear of the opening 34 is an air cooling and moisture reducing coil 37, leaning backwards, as shown in Fig. 2, to prevent condensate on the coil from being blown out onto the deflector blades 35, and directly in rear of the coil 37 is a propeller fan 38 driven by an electric motor 39. The upper portion of the rear wall 10 of the cabinet which forms the rear wall of the compartment 16 is also formed with an opening 40, and directly in front of this opening is another air cooling and moisture reducing coil 42. From this arrangement it will be seen that the fan 38 draws air across the rear coil 42, and over the motor 39, and forces the air across the front coil 37 and through the front opening 34, the direction of outflow being determined by the setting of the deflector 35.

40 Explaining the operating connections of the parts thus far described, the outlets of the two compressors 23 are connected by a pipe 43, from which a pipe 44 leads into the upper end of the condenser coil 31, in which the compressed refrigerating agent is reduced to liquid form, and is delivered through a pipe 45 to the refrigerant tank 33. From the latter, the liquid refrigerant flows upwardly under pressure through a pipe 46 to and through an expansion valve 47, and from the latter by a pipe 48 into the upper end of the front coil 37, from the lower end of which latter it flows through a pipe 49 into the upper end of the rear coil 42. From the lower end of the coil 42 the gas returns by a pipe 50 to a pipe 51 serving the intakes of the two compressors 23.

45 The condenser coil 31 is cooled by a continuously flowing body of water under pressure in housing 30. To this end, a water supply hose 52 from a water faucet or other source, equipped with a hand valve 53, leads by an extension 52' nearly to the bottom of the housing 30; outflow of the water at practically the level of the top of the coil 31 being effected by a pipe 54 leading into the top of the heat exchange coil 32. The main purpose of this latter coil is simply to absorb and carry off in the waste water the greater portion of the heat generated by the motor 22 and the compressors 23 in the bottom portion of the lower compartment 17; this being aided by a fan 32' on the inner end of the motor shaft directing the warm air onto coil 32. From the lower end of the coil 32, the water flows through a drain hose 55 to the sewer.

75 The crank cases of the two compressors are

preferably connected by a pressure equalizing pipe 56, on which is mounted an ordinary pressure gauge 57 to show the pressures existing at any time within the compressors 23.

The cooling coils 37 and 42 in the upper compartment, across which the air is moved operate at a temperature below the dew-point of the air, and of course condense the major part of the moisture in the air, which latter, in its passage across the coils deposits dust on the coils; and to catch and dispose of the dust and drippings, we provide beneath said coils a shallow pan 58 formed with a substantially central well or sump 59 into which the condensate drains to the level of the upper end of a drain pipe 60. This pipe 60 leads downwardly to an aspirator or ejector hose indicated at 61, which, in turn connects into drain hose 55. We have found in practice that the action of this ejector may create a slight hissing or sucking sound in the well 59; and to remedy this, we place in the well a sponge 62 overlying the upper end of the pipe 60. This sponge is, of course, continuously saturated with water, and has the effect of effectually killing the hissing or sucking noise above referred to.

In order to render the equipment thoroughly automatic and self-correcting in case of overload or overheating, we preferably employ certain auxiliary automatic controls. The opening and closing movements of the expansion valve 47 (in itself a well known and generally used device in systems of this character) are preferably automatically controlled by temperature-pressure variations in a fixed body of gas contained within a pipe 63 which at one end communicates with the valve casing, and at its other end with a bulb or coil 64 that encircles the return pipe 50 leading from the coil 42 back to the compressor. The temperature in the pipe 50 modifies the temperature and consequently the pressure of the gas within the pipe 63, which, in turn, automatically controls the movement of the expansion valve, to permit more or less of the refrigerant to pass to the coils.

65 indicates an overload safety device that is interposed in the motor circuit for the purpose of automatically interrupting the circuit in case of overload on the motor, to prevent injury to the latter. This device, which is a well known article, consists essentially of a thermal element thermostatic switch 66, shown in the diagrammatic view, Fig. 6. When the motor is running normally, the switch is closed. An overload on the motor increases the temperature of the thermal element, which in turn opens the switch.

In case the supply of cooling water to the condenser housing 30 should fail, or the pressure fall abnormally low so as to slow down the flow and thus create an inadequate cooling effect on the condenser, another switch 67 in the motor circuit is automatically opened. This switch is normally maintained closed by a bellows diaphragm 68 (Fig. 6) contained with a box 69 (Fig. 2) and acting against a switch lever 70 (Fig. 6) normally drawn to switch opening position by a spring 71. So long as the water pressure is sufficient, the switch 67 remains closed. When the pressure fails or falls to a non-workable degree, the bellows collapses, and the spring 71 opens the switch 67, thus arresting the motor until the water pressure is restored. The bellows 68 is supplied with water from the hose 52 by a branch line 72.

The hand valve 53 in pipe 52 is used to start and stop the entire system, since, when it is opened, it closes the motor circuit through switch

70, and when it is closed, switch 70 automatically opens.

From the foregoing it will be seen that the present invention provides a completely self-contained 5 air cooling, cleaning and de-humidifying unit wholly contained within a portable cabinet which can be placed at and in any convenient position within a room to be air conditioned, with the motor merely plugged into a socket in the wall, floor 10 or ceiling of the room. The water supply and drain members 52 and 55 may consist of suitable lengths of rubber hose to permit the shifting about of the cabinet; and by manipulation of the rotatable shutter 35, the cooled, cleaned, and 15 partly dried stream of air may be directed upwardly, downwardly, or to either side. The mounting of the machine elements upon a rubber soled platform effectually absorbs all vibration and eliminates noise. When the operating mechanism 20 in the lower compartment 11 requires oiling, adjustment or replacement of parts, it can readily be gotten at by simply removing the front panel 14. The walls of both upper and lower compartments are preferably equipped with heat 25 and sound insulating lining as indicated in Figs. 1 to 4 inclusive.

The mounting of the coil 37 in the inclined position shown is of practical importance and 30 distinctly advantageous as compared with the known vertical mounting of similar coils. Of course, the tendency of the fan blast is to blow condensed drops of moisture forwardly onto the louvre blades, whence they drip down into the underlying woodwork, tending to rot the same. 35 We have found by practical experiment that this defect may be entirely cured by leaning the coil backwardly so that the condensate drips directly from the coil itself into the underlying pan.

The specific details of structure and organization shown in the drawings and hereinabove described may be variously changed and modified 40 within the purview and scope of the appended claims.

We claim:

45 1. In an air conditioning device, the combination

with a cabinet formed with air inflow and outflow openings in two walls thereof respectively, of a backwardly inclined cooling coil opposite said outflow opening, a vertical cooling coil opposite said inflow opening, means for circulating 5 a cooling medium through said coils, and a fan and motor therefor located between said coils.

2. In a refrigerant apparatus of the compressor-condenser-expander circuit type, the 10 combination with a chamber, of a motor, a compressor driven by said motor, a condenser coil taking gas from said compressor, a refrigerant tank receiving liquid refrigerant from said condenser coil, and a housing for said condenser 15 coil, all located in said chamber, and a heat exchange coil receiving overflow water from said housing, and means for moving the air in said chamber across said heat exchange coil.

3. In a refrigerant apparatus of the compressor-condenser-expander circuit type, the 20 combination with a chamber, of a motor, a compressor driven by said motor, a condenser coil taking gas from said compressor, a refrigerant tank receiving liquid refrigerant from said condenser coil, and a housing for said condenser coil 25 all located in said chamber, and a heat exchange coil receiving overflow water from said housing, and a fan driven by said motor directing a blast 30 of air across said heat exchange coil.

4. In a portable air conditioning device, the 35 combination of a cabinet having opposed inflow and outflow openings in its rear and front walls respectively, a backwardly inclined front cooling coil behind said outflow opening, a vertical rear cooling coil opposite said inflow opening, a fan and fan motor mounted within said cabinet between said coils, an adjustable air-deflecting shutter in front of said outflow opening, and 40 a means housed in said cabinet for circulating a refrigerating medium through said coils.

JOHN M. FRANK.
